UNITED STATES PATENT OFFICE.

THOMAS H. ANDERSON, OF NEW YORK, N. Y., ASSIGNOR TO MAX E. BERNHARDT, OF NEW YORK, N. Y.

CIGAR CUTTER.

Application filed October 22, 1925. Serial No. 64,238.

This invention relates to cigar cutters, and has reference more particularly to a device of this class which comprises a member adapted to receive the end of the cigar or the like, a manipulating member, a perforator or cutter, and means whereby a relative movement of the receiving member and the manipulating member causes the perforator or cutter automatically to function.

10 An object of the invention is to provide a cigar cutter or punch which is simple in construction and compact in form, which can be readily carried in the pocket without inconvenience, and by means of which a cigar, stogy or the like can be expeditiously cut or punctured at its pointed or sealed end, to enable the user freely to draw the smoke through the same.

20 A further object of the invention is to provide a cigar cutter or punch which shall be automatic in operation, by means of which the cigar or the like can be perforated or punctured for a substantial distance of its length from the tip or pointed end, and 25 which, for the purpose of convenience in carrying it in the pocket, can be contracted into its smallest possible compass, and held in the contracted condition.

30 A still further object of the invention is to provide a device of this kind which operates to cut or perforate the end of the cigar by a mere relative movement of two of its parts, and thus requires no additional or secondary manipulation.

35 The invention consists in the construction and combination of parts herein set forth and described, and disclosed in the accompanying drawings, in which the reference characters indicate corresponding parts in the various views.

Figure 1 is a partial longitudinal section of one form of my invention;

Figure 2 is an enlarged section of the device, showing the same in use; and

45 Figure 3 is a fragmentary, partial, enlarged, longitudinal, section showing certain of the details of construction of the cigar cutter.

50 Before proceeding to a more detailed explanation of my invention, it should be understood that I am aware that punches or drills for perforating the ends of cigars or like articles of tobacco for smokers' use are not new. As is well known, the ordinary cigar, stogy or the like has one pointed end,

at which the wrapper is sealed in the manufacture. Before the smoker can use the same, it is necessary either to remove the sealed end or point by a transverse severance, or the cigar must be punctured or perforated, either axially or at an angle with its axis. Perforating the cigar at the point for a substantial distance in an axial direction has been found desirable, as it permits the cigar when being smoked to draw freely, and prevents the end of the wrapper from becoming unwound or tattered. To accomplish this, a small drill or the like has hitherto been used. My invention, however, provides means for, in effect, automatically performing the drilling operation without danger of injury to the cigar and with the production of an effective perforation. It will be understood that certain of the details of construction herein disclosed form no part of my invention and may be varied as is desirable or necessary.

Referring more particularly to the drawings, my cigar cutter consists essentially of two members, the receiving member A and the manipulating member B. The former comprises a hollow conical cigar end receiver 10 having a head 11, and, integral with the head, the reduced sleeve 12, all axially aligned. As is shown in Figure 2, the cigar end receiver 10 is so formed and proportioned that the pointed or sealed end of a cigar 13 may be readily introduced therein. The sleeve 12 has a helical slot 14, the end 15 of which, adjacent the head 11, is disposed circumferentially of the sleeve, that is, at right angles to the axis thereof.

The manipulating member B comprises a drill or cutter carrier 16, of cylindrical form and so proportioned that it will fit upon the sleeve 12, though not loosely, and can move freely around and longitudinally of the sleeve 12. The drill carrier has at its ends and rigidly secured thereto collars 17 and 18, between which is mounted to rotate freely a grip sleeve 19, which, for purposes of convenience, has its surface preferably roughened or knurled. Secured within the drill carrier is the drill 20 having the usual pointed end and a helical cutter groove 105 or slot 21. At its upper end, the drill has an enlargement 22, which fits tightly within the upper end of the drill carrier, which upper end is closed. It will be seen that the drill is so proportioned that it can move 110

freely within the bore of the sleeve 12, so that as the parts A and B are moved relatively to each other in a longitudinal direction, the drill can be projected into and withdrawn from the cigar end receiver. The parts are so proportioned that the sleeve can move freely in the space between the drill and the drill carrier. A fairly light helical spring 23 is positioned in this space and engages under the enlargement 22 and against the end of the sleeve 12, and tends normally to hold the parts in the position shown in Figure 1.

A pin 24 is located in suitable registering openings of the collar 18 and the drill carrier 16, and projects into the slot 14 of the sleeve 12. It will be understood that the drill and the drill carrier are rigidly secured together by means of the enlargement 22 of the drill, which is tightly fitted into the upper closed end of the carrier. Thus, the drill and the carrier move together, both axially and rotatably.

When the device is not in use and is carried in the pocket or elsewhere, the parts A and B are so disposed that the collar 18 rests against the head 11. A slight turning movement of the part B causes the pin 24 to enter the transverse part 15 of the slot 14, and serves to hold the parts A and B in contracted position against the tension of the spring 23. When it is desired to use the cutter, the member B is turned so that the parts assume the position shown in Figure 1. The pointed end of the cigar is then introduced into the receiver 10, the part B being grasped by means of the grip sleeve 19. Thereupon, a simple movement of telescoping the two parts A and B causes the latter to advance towards the cigar end receiver, the pin 24 moving within the slot 14, and causing the drill carrier and the drill to revolve within the grip sleeve. At the same time, the drill is projected as indi-

cated in Figure 2, forming a smooth and deep perforation in the direction of the length of the cigar. The latter, when the cutter is withdrawn, is then ready to be smoked.

Having thus described my invention, what I claim is:

1. A cigar cutter comprising a cigar end receiver, a sleeve connected thereto provided with a helical slot, a drill carrier mounted upon said sleeve and movable thereon, a drill secured to said drill carrier and movable within said sleeve, a pin secured to said drill carrier and projecting into the helical slot of said sleeve, a spring surrounding said drill within said carrier and tending to hold said drill retracted from said receiver, and a grip sleeve mounted to freely turn upon the outer surface of said drill carrier.

2. A cigar cutter comprising a cigar end receiver, a sleeve connected thereto provided with a helical slot, a drill carrier mounted to move upon said sleeve, a drill secured within said carrier and arranged to move within said sleeve, a pin secured to said carrier and projecting into said helical slot, a grip sleeve surrounding and loosely mounted upon said carrier, said drill having an enlargement at the upper end thereof, and a helical spring mounted upon said drill engaging said enlargement at one end and the slotted sleeve at its other end.

3. A device of the class described, comprising a cigar end receiver having a sleeve, a drill mounted to move within said sleeve, said sleeve having a helical slot, the lower end of said slot being disposed at right angles to the axis of said slot, a drill carrier secured to said drill, a pin carried by said carrier and projecting into said slot, means tending normally to withdraw said drill from said sleeve, and a grip sleeve surrounding and loosely mounted upon said carrier.

THOMAS H. ANDERSON.
